CLAIM

The ornamental design for a pet metal crate, as shown and described.

DESCRIPTION

FIG. 1 is a top, front and right side perspective view of a pet metal crate showing my new design;

FIG. 2 is a bottom, rear and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 in FIG. 1;

FIG. 10 is an enlarged view of portion 10 in FIG. 1;

FIG. 11 is an enlarged view of portion 11 in FIG. 1;

FIG. 12 is an enlarged view of portion 12 in FIG. 1;

FIG. 13 is an enlarged view of portion 13 in FIG. 2;

FIG. 14 is an enlarged view of portion 14 in FIG. 2;

FIG. 15 is an enlarged view of portion 15 in FIG. 2;

FIG. 16 is an enlarged view of portion 16 in FIG. 2; and,

FIG. 17 is a perspective showing the pet metal crate with its bottom plate detached from the crate.

The evenly dashed broken lines in FIG. 1, FIG. 3 and FIG. 11 illustrate portions of the pet metal crate. The unevenly

(Continued)

dashed broken lines define the boundaries of enlarged views.
None of broken lines form part of the claimed design.
